UNITED STATES PATENT OFFICE.

ALBERT W. WILSON, OF SAN FRANCISCO, CALIFORNIA.

NECKTIE HOLDER.

Application filed May 9, 1925. Serial No. 29,170.

To all whom it may concern:

Be it known that I, ALBERT W. WILSON, a citizen of the United States, and a resident of San Francisco, in the county of San Francisco and State of California, have invented a new and useful Necktie Holder, of which the following is a specification.

This invention relates to necktie holders and has for its primary object the provision of a new and novel construction of device of this character whereby a previously knotted necktie can be readily attached to or removed from a collar button in such manner that the knot of the necktie can be drawn up under the folds of the collar or across the joint at the meeting ends.

Another object of the invention is to provide a device of this character which will be positive of action, light of weight, strong, durable and of a form and design whereby its parts will be concealed when in use.

With the above and other objects in view which will be apparent as the nature of the invention is better understood, the same consists in the improved construction and novel arrangements of parts which will herein-after be fully described and particularly pointed out in the claim.

In the accompanying drawings has been illustrated a single and preferred form of the invention, it being, however, understood that no limitations are necessarily made to the precise structural details therein exhibited, but that changes, alterations and modifications within the scope of the claim may be resorted to when desired.

Figure 1 is a front view of the device attached to a collar;

Figure 2 is a perspective view of the device separated from the collar and from the tie;

Figure 3 is a vertical section taken on line III—III of Figure 2; and

Figure 4 is a transverse section taken on line IV—IV of Figure 2.

In carrying the invention into practice, I employ a tie form 5 consisting of a vertical shank 6, an upper arcuate member 7 and a suspending element 8. The form is constructed so that a tie may be wrapped thereabout so as to produce a knot 9 around the shank 6 and medially about the member 7, as shown in Figure 1. When this is accomplished, the extreme ends of the wings 10 protrude laterally beyond the knot so that

these wings may be inserted between the folds of the collar A as shown in dotted lines in Figure 1.

It is stated that the member 7 is of arcuate form, and it would be well to make clear that aside from being curved downwardly from the extreme tips of the wings so as to properly bring the upper end of the knot in the desired position, it is curved longitudinally so as to conform to the curvature of the neck, permitting the terminals of the wings 10 to lie closely against the inner folds of the collar.

The shank 6 is preferably constructed from a single piece of spring sheet metal so as to provide a front lead 11 and a rear lead 12. These leads are disposed substantially in parallelism, and the connecting bend between the leads is extended through a slot 13 in the member 7 and the leads upset 70 against each other at 14 beneath said member 7. The rear lead 12 is formed with a vertical slot 15 through which the flexible lace 16 of the suspending element passes. This lace always has a portion interposed 75 between the respective leads 11 and 12 of the shank 6 whereby these leads may be advanced against the tape to hold same against sliding with respect to the shank. The upper end of the tape is provided with a button 80 engaging plate 17 having a keyhole slot 18 adapted to be passed over the front collar button.

In this manner it will be observed that after the tie is properly arranged upon the form, the keyhole slot of the suspending element 8 can be placed over the aforesaid front collar button and the form moved upward until the knot of the tie is operatively positioned with respect to the two folds of the collar in front of the joint. When this is accomplished, a clamping band 19 on the shank is moved downward so as to bring the two leads 11 and 12 into effective clamping impingement with the lace or tape 16.

I have now described a necktie holder which is extremely simple of construction, practical for every purpose to which the invention is put, and one which embodies parts that are entirely concealed when the tie is worn. It will also be appreciated that by means of the flexible tape 16 constituting part of my novel suspending element 8, the knot of the tie can be drawn up with respect to the folds of the collar so as 110

to always present a neat and dressy appearance. When it is desired to release the tie from the collar, the clamp 19 is drawn in an upward direction and the form 5 moved downward so as to free the knot from between the folds of the collar. The suspending element is then pushed upward until the head of the front collar button alines with the larger part of the aforesaid key-
10 hole slot.

I claim:

As a new article of manufacture, a necktie holder comprising a form including a vertical shank having relatively separable leads, a tape movable between the leads and provided with means to engage with a collar button and means sliding on the shank for gripping the leads against the tape. 15

ALBERT W. WILSON.
